LIGHTING FIXTURE CONSTRUCTION

Joseph Levy, New York, N. Y., assignor to Century Lighting, Inc., a corporation of New York

Application November 26, 1937, Serial No. 176,451

6 Claims. (Cl. 240—78)

This invention relates to the lighting fixture art and more particularly is directed to the electrically lighted illuminating fixture construction for projecting light beams either as spot or flood light in various directions.

Among the objects of the invention is to generally improve lighting fixture constructions of the character described which shall comprise few and simple parts that are readily assembled and adapted to form interior electric lighting fixtures of attractive appearance, which shall be easily adjusted for projecting light beams as spot and flood light in various desired directions, which shall be inexpensive to manufacture and practical and efficient to a high degree in use.

Other objects of this invention will in part be obvious and in part hereinafter pointed out.

The invention accordingly consists in elements of construction, combination of elements and arrangement of parts which shall be exemplified in the construction herein described and of which the scope of the invention will be indicated in the following claims.

In the accompanying drawings in which is shown various possible illustrations of this invention,

Fig. 1 is a front elevational view of a ceiling surface mounting type of electric lighting fixture adapted to be used for interior illumination constructed to embody the invention, parts being broken away to expose the electric light bulb, the full line position of the opening in the radially adjustable bottom closure being shown when directing the light beams downward from the fixture and in dotted line when said opening adjustable closure is positioned to project the light beams to one side instead of downward.

Fig. 2 is a bottom plan view of the fixture shown in full lines in Fig. 1, partly broken away to expose the lamp receptacle and bulb.

Fig. 3 is an enlarged cross-sectional view taken on line 3—3 of Fig. 2.

Fig. 4 is a detailed view as seen on lines 4—4 in Fig. 2.

Fig. 5 is a cross-sectional view taken on lines 5—5 in Fig. 4.

Fig. 6 is a cross-sectional view taken on lines 6—6 in Fig. 3.

Fig. 7 is a perspective view of the ring member for mounting the lens in the opening of the radially adjustable closure.

Fig. 8 is a front elevational view similar to Fig. 1 showing an embodiment of the invention applied to lighting fixtures of the ceiling recessed

mounting type with the light beams directed downward from the fixture.

Fig. 9 is a bottom elevational view of the fixture shown in Fig. 8, and

Fig. 10 is an enlarged detailed cross-sectional view taken on line 10—10 in Fig. 9. In dotted lines the opening adjustable closure is indicated when projecting the light to one side instead of downward.

Referring now to the drawings 20 denotes a 10 ceiling surface mounting type of electric lighting fixture constructed to embody the invention and adapted to be used for interior illumination for dwelling, show rooms, display windows, and other purposes, particularly where a stationary 15 lighting fixture is required to project spot or flood light in various desired directions.

As seen from Figs. 1, 2 and 3, the fixture 20 is mounted against the finished surface S of ceiling C or other support in which an outlet box 11 is 20 embedded, said box 11 being of any standard construction terminating a building wiring system for supplying electric power in the well known manner (not shown) for lighting the fixture 20.

The construction of fixture 20, as seen from Fig. 3, may include a circular shaped back plate 12 adapted to contact the finished ceiling surface S, said plate 12 being retained in position by any suitable anchoring fastener, such as spaced screws 12a. Supported to extend down from said plate 12 are spaced bolts 13 which have rigidly secured thereto inner ends 14a of Z-brackets 14, the outer end 14b of said brackets 14 may be fastened by any suitable means as bolts 14c, 35 in superimposed relation to an outturned flange 15a of a cylindrical housing 15. The flange 15a is also similarly fastened in superimposed relation by said bolts 14c to angle pieces 14d, the latter being secured to an inner upturned rim flange 16a of a 40 base ventilating baffle annulus 16 by bolts 14e. The annulus 16 is formed preferably of a bent or spun sheet metal gracefully shaped and terminating at its outer rim in a bead 16b adapted to extend around the periphery of the back 45 plate 12.

The diameter of the cylindrical housing 15 may be made smaller in diameter than the inner diameter of the annulus 16, the latter being positioned in concentric relation to said housing 15 to 50 provide air passages 17 between the annulus 16 and housing 15, forming ventilating means as indicated by the dotted arrow line in Fig. 3.

The above described assembly provides the stationary or relatively fixed portions of the fixture 55

- 28 and forms with a bottom closure or shell 18 a casing for enclosing a light source mounted for radial movement with said shell 18 in the manner now to be described.
- 5 Said closure or shell 18 as seen from Figs. 1, 2 and 3 comprises a hollow hemi-spherical shaped bowl or bell provided with an outward turned flange 18a, the bowl 18 with housing 15 forming a socket type of radially swivelling joint to permit so-called "universal movement". Said housing 15 may have an inturned annulus bead 15b serving as a seat for the bowl 18, said flange 18a cooperating with the seat to limit the said movement and prevent dislocating the universal joint after assembly.
- 10 The bowl 18 has mounted to move therewith a lock ring 18b which extends around the perimeter of an opening 18c, and secured to said ring 18b by any suitable means, as screws 19, is an offset upstanding arm 30. An angle carrier 21 is slidingly fitted to move on said arm 30 and through a slotted portion 30a thereof, a suitable adjustment screw mechanism 22 being provided for moving and retaining said carrier 21 at desired distances from said opening 18c.
- 15 Said carrier 21 has secured to move therewith a lamp receptacle 23 in which an electric light bulb 24 is mounted. The angle carrier 21 above the receptacle 23 and the bulb 24 supports a suitable reflector 25 for directing the reflected light beams from the bulb 24 to the opening 18c, suitable conductor wires 26 being provided to connect the lamp receptacle 23 to an electric power source through the outlet box 11.
- 20 The carrier 21 is seen to engage a screw 22a of the adjusting mechanism 22 through a projecting threaded lug 21a, and a lock ring 22b may be provided for retaining the screw head 22c in a fixed position against up and down movement in a seat projecting portion 30b of said arm 30. Thus, by turning the adjusting screw 22a, the bulb 24 and the reflector 25 may be moved from the position shown in Fig. 3 for providing projected spot lighting to a lowered position closer to the opening 18c for providing projected flood lighting.
- 25 Fitted into said lock ring 18b is a lens holder 27, said holder being releasably fastened to the ring 18b by any suitable means, as a bayonet joint 28, formed by slot opening 18d of a flange 18c on the ring 18b and spaced screws 29 carried by said holder 27 adapted to engage said slot openings 18d. The holder 27 may be grooved at 27a to seat a suitable lens 31 which is removably held in fixed position with relation to the holder 27 by means of a spring ring 32.
- 30 In practising the invention with the fixture 10, the parts are made and assembled as described above and shown in Figs. 1-7, inclusive, the conductor wires 26 being connected to a suitable power source preferably through an electric switch in the well understood manner (not shown). With the parts positioned as shown in Fig. 3, the optical system is so arranged that the light beams produced in the bulb 24 and reflected will be projected through the lens 31 in opening 18c as a spot light in a downward direction. The light beam may be projected in various other radial directions with a simple universal swinging movement of the closure shell 18 in its socket joint, as for example to its extreme side position shown in dotted lines in Fig. 1.
- 35 To change the character of the lighting projected from fixture 20 from a spot to flood light-

ing, all that is necessary is to vary the optical system by inserting a screw driver in the opening 18c provided in the shell 18 and turn the screw 22 until the carrier 21 with the receptacle 23 and bulb 24 is positioned closer to the lens 31.

The bulb 24 may be inspected and replaced by releasing the lens holder 27 and lens 31 by turning the bayonet joint 28 and dismounting same from the opening 18c to give access to the interior of the fixture 20. Ventilation is provided through the passages 17.

A modified form of the invention is shown in Figs. 8, 9 and 10. Here the fixture 120 is of the ceiling recessed type and the cylindrical housing 15 of fixture 20 is replaced by a casing 115 having an inturned flange ring 115b which engages the shell 18. The casing 115 may be mounted in the ceiling C or other support by an angle piece 33 and screws 34, the flange ring 115b being secured to the housing by suitable bolts 35. The ring 115b has a bead 115c serving as a seat for the shell 18 in the identical manner as described above for fixture 20. The parts of fixture 120 carried by the shell 18 may be identical to those described above for fixture 20 and are adjusted in substantially the same manner and for the same purposes.

In both these constructions the lens holder 27 may be formed with a flange 27b for attaching a suitable screen 36 for changing the color of the projected light beam passing through the lens 31.

As seen from Figs. 3 and 11, the shell 18 has the opening 18c thereof located not directly opposite or parallel to the plane of the flange 18a but rather in angular relation thereto so as to permit maximum radial adjustment in the socket joint for varying the direction of the projecting light beams passing through the lens 31 and opening 18c.

From Figs. 3 and 7 it is clear that both fixtures 20 and 120 may be used without the lens 31 and with or without the screens 36, or that a ground glass or other light dispersing means may replace the lens 31.

It will thus be seen that lighting fixture constructions are provided in which the several objects of the invention are achieved and which are well adapted to meet the conditions of practical use in an efficient manner.

As various embodiments might be made of the above invention and as various changes might be made in the embodiments above set forth, it is to be understood that all matters herein set forth or shown in the accompanying drawings are to be interpreted as illustrative and not in a limiting sense.

Having thus described my invention, I claim as new and desire to secure by Letters Patent:

1. In a lighting fixture construction of the character described the combination of an electric light source with a casing comprising a housing portion, a base baffle extending about said housing portion to provide a ventilating passage communicating the interior of the housing with the exterior of the fixture, both housing and baffle being adapted to be rigidly mounted to a support, a hemi-spherical shell portion for supporting said light source mounted for universal movement on the housing and forming a closure for the casing, said shell portion having an opening, the rim portions of said opening being located at unequal distances from the plane of the perimeter of the shell portion.

2. In a lighting fixture construction of the

character described the combination of an electric light source with a casing comprising a housing portion adapted to be rigidly mounted to a support, a substantially hemi-spherical shell portion supporting said light source, an inturned flange carried by said housing portion forming a seat to mount the shell portion for universal movement, said shell portion forming a movable closure for the casing, said shell portion having an opening, rim portions of said opening being located at unequal distances from the plane of the perimeter of the shell portion.

3. The lighting fixture construction defined in claim 2, in which a lens is removably mounted in said opening, the support of the light source on the shell including means adjustable from the exterior of the casing for varying the distance between said light source and the lens.

4. In a lighting fixture construction of the character described, in combination, a relatively stationary housing, a hemi-spherical shell movably supported by and cooperating with said housing for universal movement, the open diametrical side of said shell being enclosed in said housing, the shell having a surface opening lying in a plane in angular relation with respect to the plane of said diametrical open side for in-

creasing the effective range of the universal movement of said shell with respect to the housing, cooperating means between the housing and an inner unexposed portion of the shell to limit said universal movement, and a light source supported by said shell located to project light beams through said surface opening.

5. In the lighting fixture construction defined in claim 4, the stationary housing having a ventilating passage communicating the interior of 10 the housing with the exterior of the fixture.

6. In a lighting fixture construction of the character described, in combination, a light source adjustably mounted on a shell formed with a curved and an open side, a fixed supporting housing for movably mounting said shell to enclose said open side thereof, the curved surface of said shell having an opening located to project light beams originating at said light source, the planes of said open side and that 20 of the shell opening being constructed and arranged in angular relationship, a lens fitted in said shell opening, and an adjustable means carried by the shell for changing the character of the lighting projected by the fixture through 25 the lens.

JOSEPH LEVY.
